UNITED STATES PATENT OFFICE

JOHN E. McLAUGHLIN, OF ALTON, ILLINOIS, AND JESSE H. TREECE AND LEONARD D. SOUBIER, OF TOLEDO, OHIO, ASSIGNEES TO OWENS-ILLINOIS GLASS COMPANY, A CORPORATION OF OHIO

MACHINE FOR FORMING GLASS ARTICLES

Application filed January 22, 1930. Serial No. 422,574.

Our invention relates to machines for forming hollow glass articles. As herein illustrated, the invention is embodied in a machine of the type in which a blank mold carriage and a finishing mold carriage are arranged side by side and rotated continuously in opposite directions. Charges of glass are gathered by suction from a supply body of glass into blank molds on the blank mold carriage and formed into parisons which are then transferred to finishing molds on the finishing mold carriage. Various features of the invention, however, are adaptable to other types of glass forming machines than that herein illustrated.

An object of the present invention is to provide a machine having great flexibility in respect to the kinds of ware that can be made thereon and conditions under which the machine may be operated. To this end, there are provided various features of adjustment including means for adjusting the time of dip of the blank mold for gathering its charge, the time at which the mold is lifted from the gathering pool, the time at which it is lowered to its normal level outside the gathering pool, the times at which the blank molds are opened and closed, the time at which the neck mold is projected for transferring the parison to the finishing mold, the times for opening and closing the neck mold and the finishing mold, the period during which blowing air is supplied to the parison in the finishing mold, and various other adjustments adapting the machine for a wide variety of operating conditions.

A further object of the invention is to provide means whereby various adjustments of parts may be made while the machine is running and without interfering with its normal operation.

A further feature of the invention consists in so coordinating and combining the various adjustment features and mechanisms that when one part is adjusted, other adjustments will be made automatically or may be made manually, as may be required to harmonize the operation of all parts of the mechanism.

Other objects of the invention will appear hereinafter.

Referring to the accompanying drawings:

Fig. 1 is a plan view of a machine constructed in accordance with the principles of our invention.

Fig. 2 is a sectional elevation showing the blank mold carriage, parts being broken away.

Fig. 2A is a detail view showing mechanism for actuating a bottom plate for the blank mold.

Fig. 2B is a section at the line 2B on Fig. 7.

Fig. 3 is a sectional elevation showing the finishing mold carriage, parts being broken away.

Fig. 4 is a section at the line IV-IV on Fig. 3, showing means for rotatively adjusting the finishing mold carriage.

Fig. 5 is a fragmentary sectional elevation of parts shown in Fig. 3, but with the blowing head and mold bottom shown in their retracted positions.

Fig. 6 is a sectional plan view as indicated by the line VI-VI on Fig. 2.

Fig. 8 is a fragmentary front elevation view of a series of adjustable cam sections.

Fig. 9 is a sectional side elevation of the same.

Fig. 10 is a view showing a sectional cam controlling the opening and closing movements of the blank mold and mechanism for adjusting the cam.

Fig. 10A is a fragmentary elevation of the cam shown in Fig. 10, looking in the direction indicated by the arrow A.

Fig. 10B is a fragmentary elevation of said cam, looking in the direction of the arrow B, Fig. 10.

Fig. 11 is a plan view of the fixed section of the cam shown in Fig. 10.

Fig. 11A is a plan view of the adjustable section of the cam shown in Fig. 10.

Fig. 12 is a section at the line XII-XII on Fig. 10.

Fig. 13 is a fragmentary plan view show-

ing a finishing mold, its operating mechanism, and means for adjusting the mold.

Fig. 14 is a fragmentary sectional elevation, showing particularly a slide for operating the finishing mold, a support for the mold, and adjusting mechanism associated therewith.

Fig. 15 is a plan view showing the air drum above the finishing mold carriage and a cam for controlling the supply of blowing air to the finishing molds.

Fig. 16 is a section at the line XVI—XVI on Fig. 15, showing a blowing head and a valve controlling the supply of air thereto.

Fig. 17 is a plan view showing adjustable sectional cams for lifting and lowering the blow heads and for opening and closing the finishing molds.

Fig. 18 is an elevation of the same.

Fig. 19 is a section at the line XIX—XIX on Fig. 17.

Fig. 20 is a section at the line XX—XX on Fig. 1, showing a cam which controls the opening of the neck mold, and means for adjusting the cam, and also showing the cam which controls the projection of the neck mold for transferring a parison to the finishing mold.

Fig. 21 is a section at the line XXI—XXI on Fig. 1, showing the cam for projecting the neck mold to transfer a parison, and adjusting means for the cam.

Fig. 22 is a section at the line XXII—XXII on Fig. 1, showing the cam which controls the lowering of the plunger tip into the blank mold prior to the gathering operation.

Fig. 23 is a section at the line XXIII—XXIII on Fig. 1, showing the cam for withdrawing the plunger tip from the mold.

Fig. 24 is a plan view of the cam which controls the projection of the neck mold for the transfer operation, and means for adjusting the cam.

Fig. 25 is a developed elevation view of the cam shown in Fig. 24.

Fig. 26 is a sectional plan view at the plane indicated by the line XXVI—XXVI on Fig. 3, showing means for adjusting the finishing mold carriage horizontally about the axis of the blank mold carriage.

Fig. 27 is a part sectional view showing a blank mold, neck mold, plunger, and plunger operating mechanism.

In the following description and claims reference is frequently made to transfer "position" or "station". In either event applicants have reference to a portion of the paths of travel of the blank and finishing molds in which the blanks or parisons are transferred from the blank molds to the finishing molds. Also, where reference is made to charging "position" or "station", it is intended to merely identify a portion of the path of travel of the blank molds wherein

charges of molten glass are gathered into said molds.

Referring particularly to Figs. 1, 2 and 3, the machine comprises a blank mold carriage or table 30 and a finishing mold carriage or table 31 mounted side by side on a wheeled base or truck 32 movable on rails 33 toward and from a gathering tank 34 in which a continuous supply of molten glass is maintained.

The blank mold carriage 30 is mounted for rotation about a stationary hollow column or standard 36 bolted to a base plate 37 which in turn is bolted to the platform 32. A gear 38 fixed to the carriage 30, intermeshes with a gear 39 of equal diameter on the finishing mold carriage 31, so that the carriages or mold tables are rotated in synchronism in opposite directions at the same angular speed. The carriages may be driven by a motor 40 (Fig. 1) connected thereto through suitable gearing (not shown).

The finishing mold carriage 31 (Fig. 3) is mounted for rotation about a central hollow stationary column or standard 41 which is secured to a base plate 42 adjustably supported on the platform 32, as hereinafter fully set forth.

Referring to Figs. 1 and 2, an annular series of dip frames 43 are mounted on the blank mold carriage for swinging movement about horizontal pivots 44. Each dip frame carries a sectional blank mold 45, a sectional neck mold 46 and operating mechanism therefor. During the rotation of the mold carriage, each dip frame as it approaches the gathering tank 34 is tilted upward, as shown at the left hand side of Fig. 2, to permit the blank mold to clear the rim of the tank, is then tilted downward to bring the mold in contact with the body of glass in the tank for gathering a charge by suction, after the gather is tilted upward to again clear the rim of the tank, after which it is again tilted downward to bring the mold to its normal level which is maintained throughout the greater portion of its travel. The dip frame is preferably held in the position shown at the right hand side of Fig. 2, with the mold axis vertical, except when tilted upward to clear the rim of the tank.

The position of the dip frame relative to the mold carriage is controlled by a cam 47 (Figs. 2 and 6) on which runs a roll 48 on the dip frame. The cam 47 comprises a fixed section 47^a for tilting the frame upward during its travel through arc *a* (Fig. 6) to clear the rim of the tank, an adjustable section 47^b controlling the dip of the mold into the glass as it travels through arc *b*, an adjustable section 47^c for lifting the mold out of dip during its travel through arc *c*, and an adjustable section 47^d for again lowering the mold.

The cam section 47^d is adjustable circumferentially of the mold carriage by mecha-

nism including a hand wheel 49 on a worm shaft 50 carrying a wheel 51 running in mesh with a worm wheel 52 on the lower end of a vertical shaft 53. A pinion 54 on the upper end of said shaft runs in mesh with a rack 55 secured to the adjustable cam section 47^c. By rotating the hand wheel 49, the cam section 47^c may be adjusted either toward or from the section 47^d, thereby adjustably varying the point at which the mold is lifted out of dip. The cam sections 47^c and 47^d have telescoping portions providing an uninterrupted cam surface for all relative adjustments of the cam sections.

15 The cam section 47^b is adjustable toward and from the section 47^a by mechanism substantially like that just described including a shaft 56 on which is a hand wheel (not shown), said shaft carrying a worm 57 meshing with a worm wheel 58 on a shaft which carries a gear 59 engaging a rack on the cam section 47^b. By adjusting the cam section 47^b, the point at which the mold is brought in dip may be adjusted independently of the point at which it is lifted out of dip. The length of time the mold is in dip is represented by the arc *e* of variable length.

The cam section 47^d is adjustable circumferentially by means of a hand wheel 60 on a shaft carrying a worm 61 running in mesh with a worm wheel 62 on a shaft which carries a pinion 63 meshing with a rack 64 on the cam section 47^d.

25 The blank mold 45 comprises the usual 35 partible hinged sections. The opening and closing movements are controlled by a cam 65 (Fig. 2) on which runs a cam roll 66 on a slide 67 movable radially of the machine on guide rods 68 mounted on the dip frame. 40 The usual operating connections 69 are provided between the slide 67 and the mold 45.

The cam 65 comprises a section 65^a (Figs. 2 and 10 to 12) which is rotatively adjustable about the axis of the blank mold carriage. 45 The mechanism for effecting such adjustment comprises a pinion 70 running in mesh with a rack 71 on the cam section 65^a, said pinion being secured to a vertical shaft 72 journaled in bearing blocks 73 mounted in the hollow standard 36. A worm wheel 74 on the lower end of the shaft 72 runs in mesh with a worm 75 on a shaft 76 which carries a hand wheel (not shown). By means of the adjusting mechanism just described, the cam section 55 65^a which controls the opening of the blank mold may be rotatively adjusted to adjustably vary the time at which the blank mold is opened.

The adjustable cam section 65^a (Fig. 11A) 60 is approximately the form of a circular disk concentric with the standard 36 through the major portion of its circumference and is formed on its under surface with vertical cam walls 77 to provide a channel for the 65 cam roll 66. This channel commences at the

radial line 78 (Fig. 10) and curves inwardly toward the center of the mold carriage to provide a mold opening section, the extent of which is indicated by the arc 79 (Fig. 10). At the radial line 80 the depth of the cam 70 wall 77 is reduced, providing a comparatively narrow extension 81 (Fig. 10B) concentric with the axis of the mold carriage. The stationary cam section which underlies the adjustable section is formed with a vertical cam 75 wall 82 which, as shown in Fig. 10B, is provided with an extension 83 underlying the section 81. The sections 81 and 83 are telescopically arranged to provide an unbroken cam surface for the roll 66 in all positions of adjustment. The cam wall 82 comprises a blank mold closing portion 84 extending from the radial line 85 to the radial line 86 at which the cam groove terminates.

With the parts adjusted as shown in Fig. 85 10, the opening movement of the blank mold will commence when the cam roll 66 reaches the radial line 78 and will be completed when said roll reaches the line 80. The mold then remains open during its travel through an 90 arc 87 extending from the radial line 80 to the line 85. The closing movement then commences and is completed when the cam roll reaches the radius 86. The range of the blank 95 closing movement is represented by the arc 88.

When it is desired to effect the opening of the blank mold at a later period, the cam section 65^a may be adjusted in a counter-clockwise direction and thereby bring the cam opening section to the dotted line position (Fig. 10). The opening of the mold will then be effected during the travel of the cam roll from the radial line 89 to the line 90. The blank mold will then remain open during 100 its travel through the arc 91 extending between the radii 90 and 85. It will be noted that the time at which the blank mold is closed is not affected by adjustment of the cam. The blank mold remains closed during 105 its travel through an arc 92 when the cam is in the full line position (Fig. 10). By adjustment of the cam, the blank mold may be held closed during the additional period represented by the arc 93 extending between the 110 radii 78 and 89.

The means for applying suction to the blank mold for gathering a charge of glass will be understood by reference to Figs. 2, 2B and 7. A vacuum and air drum 94 surrounding the column 36, provides a chamber 95 divided into separate compartments by means of radial partitions 96, there being one compartment for each dip head. An air and vacuum line 97 extends from each compartment 95 to the corresponding mold. A valve 98 in the line 97 controls the periods of time intervals during which air pressure and vacuum respectively are applied to the mold. Overlying the drum 94 is a stationary plate 115

99 held against the drum by springs 100. A vacuum pipe 101 connected to the plate 99, communicates with an arc-shaped recess or channel 102 formed in the lower face of the plate 99. In each compartment of the drum is a port opening 103 extending through the upper wall of the compartment in position to register with the channel 102 as such compartment travels beneath said channel during the rotation of the drum.

The vacuum pipe 101 is connected to a constant source of vacuum and it will be seen that as a port 103 passes beneath the channel 102, communication is established from the vacuum pipe to the corresponding drum compartment 95, so that the air is exhausted therefrom. After the air has been exhausted from a compartment 95, the corresponding valve 98 is opened by means of a cam 104, so that suction is applied to the mold and a charge of glass is thereby drawn into the mold in a well known manner. The valve 98 then closes. After the mold has received its charge and is lifted from the pool, a knife plate 105 operates as hereinafter explained to sever the glass and close the bottom end of the blank mold. The usual plunger tip is then withdrawn (as hereinafter noted) and air under pressure applied for compacting the glass in the mold. For this purpose, air under pressure is supplied through a pipe 106 (Fig. 7) connected to a constant source of air pressure. This pipe is connected to the plate 99 and communicates through an opening in the plate with an arcuate channel 107 in the lower surface of said plate. Port openings 108 extending through the upper wall of the drum 94 are brought into register with the channel 107 as the drum rotates. It will thus be seen that each drum compartment 95 is brought into communication with the air pressure after the port 103 in said compartment has passed beyond the channel 102 in the vacuum line so that communication with the vacuum line has been cut off. The valve 98 is opened by means of a cam 109 to admit air pressure through the line 97 to the mold. The glass is thus compacted in the mold, after which the valve 98 closes, cutting off the air pressure.

Each of the cams 104 and 109 comprises a multiplicity of cam sections, as shown in detail in Figs. 8 and 9. Each cam section comprises a head 110 formed with a lower horizontal cam surface 111. A stem 112 integral with the head 110 extends upward through a guide plate 113. A latch 114 connected to the stem 112 by a pivot 115, is provided with a notch or recess to engage a holding rib 116 on the guide plate 113. The cam section may thus be held in its elevated or inoperative position, or may be lowered by disengaging the latch. It may be locked in its lowered position by engaging a shoul-

der 117 on the latch beneath the rib 116. The guide plate 113 is removably attached to an angle bracket 118 which is removably secured by bolts 119 to a cam supporting plate 120 which, as shown in Fig. 2, is formed integral with a hub or sleeve 121 surrounding the column 36. By adjusting the individual cam sections, the cam 104 may be adjusted to operate the valve 98 for supplying vacuum to the mold at any desired point and for cutting off the vacuum at any point independently of the time of valve opening. In like manner, the time at which the air pressure is admitted to the blank mold and the time at which it is cut off may be independently adjusted by adjusting the individual sections of the cam 109.

The knife plate 105 (Fig. 2) is carried on a bell crank lever 125 which has a pivotal connection 126 with a sleeve 127 mounted on a hollow shaft 128 which forms part of the dip frame. When the mold is lifted after receiving its charge, the knife plate 105 operates to sever the glass. The operation of the knife is under the control of a cam track 129 (Figs. 2A and 6). Fixed to the lower end of the shaft 128 is a rock arm 130 carrying a roll 131 which runs in the track 129 for rotating the sleeve 127 and thereby swinging the knife plate across the bottom of the mold to sever the glass. The knife plate is then held against the bottom of the mold, forming a closure therefor during the blowing of a parison in the mold as heretofore described. An adjusting cam 132 mounted on the shaft 128 is rotatively adjustable thereon and is formed with a cam slot to engage the lower end of the bell crank lever 125. The cam slot is so shaped that rotative adjustment of the cam will swing the bell crank lever on its fulcrum and thereby adjust the plate 105 toward or from the mold. If desired, a separate knife may be used for severing the glass at the bottom of the mold, as, for example, a stationary knife such as shown in the British patent to O'Neill, Number 315,154, July 11, 1929. The plate 105 would then serve simply as a closure for the mold bottom.

The plunger 133^a (Fig. 27) with the plunger tip for forming an initial blow opening in the parison, is actuated by a swinging arm 133 pivotally connected to a standard 134 and having operating connections 133^b with the plunger. When the arm 133 is swung up, the plunger is held in its lowered operative position by a cam 133^c on the arm 133. After the mold has received its charge, the arm 133 is swung down by means of a cam 135 (Figs. 1 and 23) to cause the plunger to be withdrawn. The cam is adjustable horizontally about the axis of the mold carriage to permit the time at which the plunger is withdrawn to be adjusted. This adjustment is effected by a hand wheel 136 on a shaft 137 journaled

on a bracket 138 having a stationary mounting. A pinion 139 on the shaft 137 engages a rack 140 attached to the cam plate 135. After an adjustment of the cam the hand wheel 136 is locked by a clamping screw 141. The cam plate 135 has a slot and pin connection 142 with a cam plate 143 formed with a cam track 144 which serves to hold the plunger in its withdrawn position.

- 10 As the blank mold with the parison therein approaches the parison transfer position, it is opened, leaving the parison supported in the neck mold 46. The neck mold with the parison therein is projected radially outward 15 for the transfer by means of a cam 145 (Figs. 1, 2, 20, 21, 24 and 25). A cam roll 146 running on the cam 145 is mounted on a bracket 147 on a neck mold carrying frame 148 mounted to slide radially of the machine on guides 20 149. The cam plate 145 is adjustable about the axis of the blank mold carriage by means of a hand wheel 150 (Figs. 1 and 21) connected to a pinion 151 engaging a rack 152 attached to the cam plate 145.
- 25 The neck mold is opened by means of the arm 133 operating through a plunger 153 which carries at its lower end a wedge for spreading the neck mold arms in a well known manner, as shown, for example, in the British Patent Number 315,154 above-mentioned.
- 30 When the plunger is retracted, as above noted, by the cam 135 and held retracted by the cam track 144, the arm 133 is not lowered sufficiently to actuate the plunger 153. When the neck mold is projected outward for the transfer, the arm 133 is moved downward sufficiently to engage the plunger 153 and move it downward a short distance for slightly opening or "cracking" the neck mold just before the corresponding finishing mold closes about the parison, thereby preventing shearing or distorting of the parison due to any slight relative movement of the neck mold and finishing mold at the moment of transfer.
- 40 After the parison is enclosed in the finishing mold, the plunger 153 is moved downward sufficiently to completely open the neck mold. This "cracking" and opening of the neck mold are effected by a cam 154 (Figs. 1, 2 and 20) operating on the arm 133. This cam is 45 adjusted by means of a hand wheel 155 having a shaft journaled in a bracket 156 mounted on the plate 120, said shaft carrying a pinion 157 engaging a rack 158 on the cam plate 154. The latter has a dove-tail sliding connection with the cam plate 145 to permit such adjustment independently of the latter cam plate.

50 The plunger tip is lowered into the blank mold prior to the charge gathering operation by means of a cam 159 (Figs 1 and 22) operating on the arm 133. The cam 159 is adjustable by means of a hand wheel 160 connected with a pinion 161 engaging a rack 162 on the cam. There is thus provided means

for adjustably varying the time at which the plunger is lowered.

Finishing molds 165 (see Figs. 3 and 13) are mounted on the finishing mold carriage 31 for receiving the parisons as they are transferred from the blank molds. Each finishing mold comprises partible sections carried on arms which pivot about a hinge pin 166 mounted in a yoke 167 on which are also mounted bell crank levers 168 connected through links 169 to the mold arms. The mold is opened and closed by means of a cam with which engages a roll 170 carried on a slide block 171 mounted to slide radially of the mold carriage in guides 172. Links 173 connect the slide 171 with the levers 168. The guides 172 are supported on a plate 176 which is integral with the mold carrying yoke 167. The plate 176 overlies and is supported on a plate 174 which is adjustably mounted on the mold carriage. Adjusting bolts 175 (Fig. 13) permit adjustment of the plate 174 about the axis of the carriage. The plate 176 which carries the mold is adjustable radially of the machine by means of an adjusting screw 177 rotatably mounted in a bracket 178 on the plate 174, said screw having a threaded connection with a lug 179 on the plate 176. By rotating the screw 177, the slide plate 176 may be adjusted radially of the machine. This, together with the means 175 for lateral adjustment, permits the mold to be adjusted horizontally in any direction so that it may be brought into accurate alignment with the neck mold at the time of transfer.

100 The cam roll 170 (Fig. 14) is carried on a block 180 which is slidably mounted on the plate 171 to permit relative adjustment of said block and plate in a direction radial to the mold carriage. Set screws 181 hold the parts in their adjusted position. By loosening the set screws, the slide plate 171 is free for adjustment radially of the mold carriage while the guide roll 170 is held by its cam.

110 A bottom plate 182 (see Fig. 5) for the finishing mold is carried on a swinging frame 183 having a pivotal connection 184 with the plate 176 which supports the blank mold. A rod 185 connected at one end to the frame 183 and at its inner end to the slide plate 171, controls the swinging movement of the frame 183 for lifting and lowering the mold bottom. When the slide plate 171 is moved outward to close the finishing mold, it operates through the rod 185 to swing the mold bottom up so that the finishing mold sections close around it and thereby lock it in position. The rod 185 comprises sections having a telescopic connection including a housing 186 in which is a spring 186^a for holding said sections normally extended. This construction permits the mold bottom to be brought up to its operative position before the finishing mold sections have completed their closing movement, the frame 183 being held up under spring 120 125 130

5 tension during the final closing movement of the mold. When the finishing mold opens, the mold bottom does not commence its downward movement until the mold sections have cleared the bottle or other article formed in the mold. The mold bottom 182 is removably held in a carrier 187 mounted for adjustment up and down in the frame 183 and held in its adjusted position by a set screw 188.

10 A blowing head 190 (Figs. 3, 5 and 16) is mounted in a frame 191 having a pivotal connection 192 with the finishing mold carrying frame. The frame 191 is swung about its pivot for lifting and lowering the blowing head by means of a cam 193 which operates a slide plate 194 connected through a rod 195 to the frame 191.

15 The mechanism for controlling the supply of air to the blowing head will be understood by reference to Figs. 3, 15 and 16. An air pressure pipe 196 connected to any suitable source of air under pressure, maintains a constant air pressure in a chamber 197 formed in a stationary head 198 mounted on the column 41 above a rotating drum 199 formed with an annular air chamber 200. The air chamber 197 is in constant communication with the chamber 200 through ports 201. Air lines individual to the blowing heads extend from the chamber 200 to said heads. Each said line includes a pipe 202 extending from the chamber 200 to a valve 203, a pipe 204 extending from the valve to the hollow pivot 192, and a pipe 205 extending from said pivot to the blowing head. The valve 203 is opened and held open during a predetermined arc of travel of the finishing mold by a cam 206 comprising a multiplicity of adjustable sections which may be of the construction shown in Figs. 8 and 9. The cam, as shown in Fig. 15, extends through an arc of substantially more than 180 degrees, and by adjustment of the cam sections may be made to hold the valve 203 open and supply air pressure to the finishing mold during its travel through any desired portion of said arc.

20 The cam for opening and closing the finishing molds (see Figs. 3 and 17 to 19) comprises a fixed cam section 207 and an adjustable section 207^a. The adjustable section is formed with a rack 208 engaged by a pinion 209 on the upper end of a shaft 210 having bearings in blocks 211 in the center column 41 of the carriage. A worm wheel 212 on the lower end of the shaft engages a worm 213 on a shaft 214 carrying a hand crank 215 (see Fig. 1). By rotating the crank 215, the cam section 207^a is adjusted about the axis of the mold carriage to adjustably vary the point at which the finishing mold is opened.

25 The cam 193 for operating the blowing head comprises an adjustable section 193^a which is bolted to the adjustable section 207^a of the finishing mold cam and is adjustable therewith. The cam section 193^a is arranged

to lift the blowing head just before the finishing mold is opened, and any adjustment of the cam section 207^a for changing the time of opening the mold will correspondingly adjust the time of lifting the blowing head.

30 The finishing mold carriage 31 and its supporting column 41 are adjustable bodily as a unit in a horizontal direction about the axis of the blank mold carriage, as will be understood by reference to Figs. 1, 3 and 26. For the purpose of such adjustment, the base 42 is formed on its under surface with ribs 216 which are slidable in arc-shaped grooves 217 in the platform 32, said grooves being concentric with the blank mold carriage. Bolts 218 extend through arc-shaped slots 219 in the plate 42 and have a threaded connection with the platform 32, thus preventing vertical displacement of the base plate 42. The adjustment is effected by means of a hand crank 220 on a shaft 221 carrying a worm 222 running in mesh with rack teeth 223 on the base plate 42.

35 By means of the adjusting mechanism just described, the finishing mold carriage may be adjustably moved forward or backward around the axis of the blank mold carriage to correspond to any adjustment of the neck mold projecting cam 145. The finishing molds may thus be caused to close around the parison in synchronism with the transfer movements of the neck mold, for any adjustment of the transfer station about the axis of the blank mold carriage.

40 It will be noted that any translatory adjustment of the finishing mold carriage about the axis of the blank mold carriage in the manner above described, will cause the gear 39 to roll on the gear 38, so that the angular or rotative position of the finishing mold carriage relative to the blank mold carriage is changed in a manner which would prevent proper registry of the neck mold and finishing mold at the time of transfer. To compensate for this, there is provided means for 45 rotatively adjusting the finishing mold carriage about its axis. Such adjusting means is shown in Figs. 3 and 4 and comprises a hand wheel 224 (Fig. 4) on a worm shaft journalized in bearings 225 on the hub of the gear wheel 39. The worm meshes with a worm wheel 226 which is secured to the hub of the mold carriage. By rotation of the hand wheel 224, the mold carriage may be adjustably rotated.

45 Modifications may be resorted to within the spirit and scope of our invention.

50 What we claim is:

1. A machine for forming glass articles comprising a blank mold carriage, blank molds thereon, a finishing mold carriage, finishing molds thereon, a base on which said carriages are mounted side by side for rotation about vertical axes, gearing interconnecting said carriages whereby they are rotated

in synchronism, automatic means for transferring parisons from the blank molds to the finishing molds, means for adjusting one of said carriages horizontally about the axis 5 of the other carriage, and means for relatively adjusting one of said carriages about its own axis while the other carriage is stationary.

2. A machine for forming glass articles 10 comprising a blank mold carriage, blank molds thereon, a finishing mold carriage, finishing molds thereon, a base on which said carriages are mounted side by side for rotation about vertical axes, gearing interconnecting said carriages whereby they are rotated in synchronism, said gearing including a gear connected to one of said carriages for rotation therewith, adjusting means for effecting a relative rotation of said gear and 15 its carriage, and automatic means for transferring parisons from the blank molds to the finishing molds.

3. A machine for forming glass articles comprising a blank mold carriage, blank 20 molds thereon, a finishing mold carriage, finishing molds thereon, a base on which said carriages are mounted side by side for rotation about vertical axes, gearing interconnecting said carriages whereby they are rotated in synchronism, said gearing including a gear connected to one of said carriages for rotation therewith, adjusting means for effecting a relative rotation of said gear and 25 its carriage, said adjusting means including a worm wheel mounted on the carriage concentric therewith, a worm mounted on said gear, and running in mesh with said worm wheel, and manual means for rotating said worm.

4. In a machine for forming glass articles, the combination of a mold carriage rotatable about a vertical axis, a driving element mounted for rotation with the mold carriage about said axis, adjusting means for effecting a relative rotation between said driving element and the mold carriage, said adjusting means comprising a worm gear fixed to the mold carriage, a worm in mesh therewith mounted on said driving element, and means 50 for rotating said worm.

5. In a machine for forming glass articles, the combination of blank and finishing mold tables mounted side by side for rotation about vertical axes, blank molds and finishing molds mounted on said tables respectively, a transfer device mounted on one of said tables for transferring a parison from a blank mold to a finishing mold, means for operating said transfer device, adjusting 55 means for adjustably varying the point at which during the rotation of the mold tables said transfer device operates, and means for adjusting one of the mold tables about the axis of the other mold table.

6. The combination of a blank mold car-

riage, a blank mold thereon, a finishing mold carriage, a finishing mold thereon, said carriages mounted side by side for rotation about vertical axes, a parison transfer device, a stationary cam, operating connections 70 between said cam and the transfer device for causing the latter to transfer a parison from the blank mold to the finishing mold when the carriages reach a predetermined position of rotation, means for adjusting said cam 75 about the axis of the blank mold carriage, and means to adjust the finishing mold carriage and thereby adjust the position of the finishing mold to correspond to the change in the position of the transfer device at the 80 time of transfer due to said adjustment of the cam.

7. The combination of a blank mold carriage, a blank mold thereon, a finishing mold carriage, a finishing mold thereon, said carriages mounted side by side for rotation about vertical axes, a parison transfer device, a stationary cam, operating connections 85 between said cam and the transfer device for causing the latter to transfer a parison from the blank mold to the finishing mold when the carriages reach a predetermined position of rotation, means for adjusting said cam about the axis of the blank mold carriage, means for adjusting the finishing mold 90 carriage horizontally about the axis of the blank mold carriage, and separate means for relatively adjusting the finishing mold carriage.

8. The combination of a mold carriage rotatable about a vertical axis, a mold thereon comprising separable sections, a stationary cam, a slide plate mounted on the mold carriage for movement radially thereof, operating connections between said slide plate 105 and mold sections, operating connections between the slide plate and said cam, and means for adjusting the slide plate transversely of its said radial movement.

9. The combination of a mold carriage rotatable about a vertical axis, a mold comprising separable sections, a support on which the mold is mounted, said support being mounted on the mold carriage, means for adjusting said support radially of the mold 110 carriage, separate means for adjusting said support horizontally in a direction transverse to said first mentioned adjustment, a stationary cam, a slide plate mounted for movement radially of the mold carriage, operating connections between the slide plate 115 and the mold sections, a cam roll running on said cam, means connecting said roll to said slide plate, and adjusting means for effecting a relative adjustment between said 120 roll and said slide plate in a direction radial to the mold carriage.

10. The combination of a mold carriage rotatable about a vertical axis, an annular series of molds thereon, each comprising 125

130

horizontally separable sections, means for individually adjusting the molds each in a direction radial to the mold carriage, means for individually adjusting the molds circumferentially of the mold carriage, a stationary cam, mechanism actuated by said cam for operating the mold sections, and adjusting means between said mechanism and cam by which said mechanism may be adjusted to correspond to adjustments of the mold.

11. The combination of a mold carriage mounted for rotation about a vertical axis, an annular series of molds thereon, an air and vacuum drum mounted for rotation with the mold carriage and comprising an annular chamber divided into a plurality of compartments corresponding in number to the molds of said series, air lines leading from said compartments to the respective molds, means for connecting each said compartment alternately with air pressure and vacuum during each rotation of the mold carriage, a valve in each air line, a cam controlling each said valve while the corresponding said compartment is connected with air pressure, and a separate cam controlling each said valve while the corresponding compartment is connected with said source of vacuum, each of said cams being adjustable to adjustably vary the points at which the valves are opened and closed.

12. The combination of a mold carriage mounted for rotation about a vertical axis, an annular series of molds thereon, an air and vacuum drum mounted for rotation with the mold carriage and comprising an annular chamber divided into a plurality of compartments corresponding in number to the molds of said series, air lines leading from said compartments to the respective molds, means for connecting each said compartment alternately with air pressure and vacuum during each rotation of the mold carriage, a valve in each air line, a cam controlling each said valve while the corresponding said compartment is connected with air pressure, and a separate cam controlling each said valve while the corresponding compartment is connected with said source of vacuum, each of said cams comprising a multiplicity of adjustable sections by which the times of opening and closing the valves may be separately adjusted.

13. In a machine for forming hollow glass articles, the combination of a blank mold carriage, suction gathering blank molds thereon, co-operating neck molds, a finishing mold carriage, finishing molds thereon, said carriages arranged side by side for rotation about vertical axes, means for dipping the

blank molds and gathering charges of glass by suction, means for opening and closing the blank molds, means for opening and closing the neck molds, means for projecting the neck molds for transferring parisons to the finishing molds, means for opening and closing the finishing molds, blowing heads movable to and from the finishing molds, cams for controlling the opening and closing movements of the molds and for actuating the blowing heads, and adjusting means for adjusting the cams and for adjustably varying the time of opening and closing of each of said molds, the movements of the blowing head and the projection of the neck mold for the transfer.

14. A machine for forming glass articles, comprising a blank mold carriage, a blank mold thereon, a finishing mold carriage, a finishing mold thereon, said carriages arranged side by side for rotation about vertical axes, means for rotating said carriages in synchronism and periodically bringing the blank mold and finishing mold to a parison transfer position, automatic means for transferring a parison from the blank mold to the finishing mold at said position, automatic means for introducing charges of molten glass into the blank mold at a charging position, adjusting means for moving the transfer position circumferentially of the blank mold carriage in a direction to increase the distance through which the blank mold travels in its passage from the charging position to the transfer position, and means for rotatably adjusting one of the mold carriages independently of the other for synchronizing the relative rotative positions of the mold carriages to correspond to said first mentioned adjustment.

15. A machine for forming glass articles comprising a stationary base, a blank mold carriage rotatably mounted on one end of the base, a finishing mold carriage support mounted on the other end of the base for adjustment in a horizontal plane about the axis of rotation of the blank mold carriage, worm and gear mechanism for adjusting the position of said support about said axis, and a finishing mold carriage rotatably mounted on said support.
